FLYING BIRD TOY

Lawrence M. Rheingold and Alfred P. Rheingold,
Brooklyn, N. Y.

Application January 11, 1946, Serial No. 640,430

1. Claim. (Cl. 46—51)

1

This invention relates in general to a toy and in particular to a toy simulating in appearance and in action a flying bird.

It is well known that among a child's favorite toys are almost invariably motion producing toys of one sort or another. Accordingly, it is an object of this invention to provide a moving toy.

It is a further object of this invention to provide a bird-like toy.

It is another object of the invention to provide a toy which simulates in appearance and in action the appearance and action of a bird in flight.

Additional objects of the invention as well as its construction, use, and operation will in part be obvious and will in part become apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a toy according to one form of the invention.

Fig. 2 is a fragmentary side elevational view in cross section of the article shown in Fig. 1, taken along the line 2—2.

Fig. 3 is an exploded perspective view of a portion of a toy according to a further form of the invention.

Fig. 4 is a cross sectional view of the toy shown in Fig. 3, taken along the line 4—4.

Fig. 5 is a fragmentary perspective view of a toy wing according to the form of the invention shown in Figs. 4 and 5.

Referring to the figures in detail, Figs. 1 and 2 show one form of the invention comprising a toy bird generally designated 10, which is formed of a head 12 mounted on an elongated handle member 11, having a pair of wings 13 and 14 rotatably mounted thereon, and having a plurality of spacers 15 positioned on the stick adjacent to the wings.

The handle member 11 is round in cross section, and preferably formed of wood, plastic, or the like. It is notched at its forward end 16, to receive the head member 12.

The head member 12 is a member preferably cut or formed in the outline of a bird's head and fitted into the notched end 16 of the stick. The head member 12 may be formed in any desired outline such as the head of any animal or bird,

or even in a fanciful form; however, it will be understood that the presently preferred form of the invention contemplates a head in the outline of a relatively large bird such as an eagle or the like, so that the entire toy will be in proportion to the size of the head, and at the same time the head will be in proportion to the life size of the bird. The head member 12 will suitably be constructed of a thin board-like material such as cardboard, plywood, or the like.

According to one form of the invention, the head member is comparatively permanently mounted on the handle member 11 by means of glue, nails, staples or the like. According to another embodiment of the invention the head member is replaceably mounted on the handle member 11 by a snug frictional fit between the head member 12 and the notched end 16 of the handle member. According to this latter form of the invention, one toy can interchangeably become any one of a variety of different birds or other objects. If desired, the head member might also be replaceably secured by means of a hinge member wherein the pin would serve the purpose of assembling and disassembling.

Positioned behind the notched end 16 are a plurality of spacers 15 or washers, which serve to outline at least two separated portions of the stick on which are rotatably mounted the two wing members 13 and 14. The spacers 15, preferably three in number, are conventional disk-like forms, fixed in position on the member 11, for example, by means of adhesive or friction fit. The wing members 13 and 14 are shaped to simulate a bird's wings, being substantially mirror images of each other. The wing members have holes 17 therethrough, the holes being slightly bigger than the diameter of the handle member 11, and these holes serve to mount the wings 13 and 14 for rotation relative to the handle member 11. Preferably there is only one hole 17 to each wing member; however, there may optionally be a plurality of holes 17 for each wing, in which case the wings may be adjustably mounted on the member 11.

The operation of the device is simple, and at the same time a surprisingly fine illusion is created whereby an actual bird appears to be flying through the air. One of the wing members, for example rear wing 13, is held substantially motionless while the toy is twirled to impart a rotary motion to the other wing which is left free to move around the handle member 11. After this front wing 14 is properly moving, the rear wing 13 is released at the proper time,

whereby it begins to move in the opposite direction. It is noted that it is necessary to have the wings moving in opposite directions, and also that it is preferable to have each wing moving downward when it is outstretched and on its correct side of the handle member 11. In Fig. 1, accordingly, wing 14 will be moving in a counter-clockwise motion when viewed from the rear by the person operating the toy, whereas the front wing 13 will be moving in a clockwise direction.

The necessity for opposite motion of the wing members 13 and 14 requires a little practice in operation, and accordingly it affords a child a feeling of accomplishment when he is able to make the toy work properly. However, once a child or adult learns the knack of using the toy there is substantially no difficulty at all in its operation. On the other hand, the created illusion that a bird is flapping its wing during flight through the air does not disappear with familiarity, and therefore the toy does not rapidly become neglected.

In Figs. 3, 4, and 5 there are shown further details in the construction and operation of the toy, together with a further form or embodiment of the invention. For example, in Fig. 3 there can be seen with greater clarity the joining together of the head member 12^a with the handle member 11^a, through a notch 18^a in the end thereof. Reference is had to the notched end 16 of the stick as set forth in connection with Figs. 1 and 2 and as shown herein in Fig. 3.

Also shown in Figs. 3 to 5 is a form of the invention in which reverse motion of the wing members is substantially prevented. In this form of the invention the wing member 13 or 14 (see Fig. 5 which shows a fragment of wing member 13) is provided with at least one tooth 20 which is pointed to resist motion in the incorrect direction while permitting free motion in the correct direction. This tooth, for example positioned around the edge of hole 17 in the wing member, is adapted to engage a similar but opposing tooth 19 in the handle member 11^a. In this form of the invention the wing members 13 and 14 optionally are positioned in channels 18 running around the stick, and tooth 19 is likewise positioned in each channel 18. Accordingly the wings 13 and 14 are constantly in a position to engage the stick to prevent motion in the reverse direction by the abutting reverse tooth 19.

In the form of the invention shown in the figures, there is a loose fit between the wing member 14 (or 13) and the handle member 11, so that there is substantially no resistance to motion unless the teeth are engaging in opposing motion. This also permits a certain "looseness" in motion which further simulates the appearance of a bird's wings in flight.

The toy shown in Figs. 3 to 5 is similar in operation to the bird shown in Figs. 1 and 2. In fact,

the operation may be identical if so desired. However, it generally will not be necessary to hold the one wing while spinning the other; on the contrary, it will generally be possible to start both wings in motion at the same time, inasmuch as the teeth will prevent reverse motion in the starting period.

Numerous variations and modifications may be made in the invention without departing from the scope thereof. For example, in Figs. 3 to 5 the spacers 15 are not shown. It is understood that these spacers are to be present in the preferred form of the invention; however, when the wings 13 and 14 are correctly fitted in the channels 18 these spacers are not strictly necessary for the operation of the toy, and accordingly the spacers may, if desired, be omitted. Likewise, numerous variations in design and structure may be made, as well as numerous minor refinements in its construction.

While we have illustrated and described the preferred embodiments of our invention, it is to be understood that we do not limit ourselves to the precise constructions herein disclosed and the right is reserved to all changes and modifications coming within the scope of the invention as defined in the appended claim.

Having thus described our invention, what we claim as new, and desire to secure by United States Letters Patent, is:

In a toy having an elongated handle member formed adjacent one end with spaced channels and wing members formed at their inner ends with holes of a diameter slightly less than the diameter of the handle member and through which the material of the handle member within the channels passes for rotatively retaining the wing members in position on the handle member against longitudinal movement relative thereto, a single ratchet tooth formed in each of the channels, said ratchet teeth being extended in opposite directions, and ratchet teeth formed in the material of the wing members defining the holes, said ratchet teeth of each wing member being arranged in opposition to said ratchet tooth of the respective channel for limiting rotation of each wing member to rotation in one direction and in opposition to each other.
